CLAIM

I claim the ornamental design for a modesty panel for a desk, as shown and described.

DESCRIPTION

FIG. 1 is a top, front, right side perspective view of a modesty panel for a desk embodying my new design;

FIG. 2 is a front elevational view of FIG. 1;

FIG. 3 is a right side elevational view of FIG. 1, the left side elevational view being a mirror image thereof;

FIG. 4 is a rear elevational view of FIG. 1; and,

FIG. 5 is a cross sectional view along section line 5—5 of FIG. 2.

1 Claim, 2 Drawing Sheets
